Fig. 3

Fig. 1

Fig. 4

FIGURE 1 is an elevational view of a container for dairy products or the like showing my new design;

FIGURE 2 is a top plan view thereof;

FIGURE 3 is a bottom view thereof; and

FIGURE 4 is a development view of the main side wall portion thereof.

The dominant features of my design reside in the portions shown in full lines, the lined background representing contrasting shading.

I claim:

The ornamental design for a container for dairy products or the like, substantially as shown and described.
